United States Patent Office

Des. 187,388
Patented Mar. 8, 1960

187,388

TISSUE DISPENSER

Isaac Lum, Honolulu, Hawaii

Application June 26, 1957, Serial No. 46,735

Term of patent 14 years

(Cl. D52--2)

The characteristic features of my design for the tissue dispenser disclosed reside in the open side portions having the configuration shown.

I claim:

The ornamental design for a tissue dispenser, as shown and described.
